UNITED STATES PATENT OFFICE

2,293,962

OSCILLATOR

Robert William Baily, Narberth, Pa.

Application March 25, 1940, Serial No. 325,820

5 Claims. (Cl. 94—48)

My present invention relates to an apparatus and method for imparting vibrations to a mass of material, such as concrete, which becomes plastic when vibrated, the nature of the vibrations being alternating oscillations which when imparted to the mass cause it to become more homogeneous.

This application is a continuation-in-part of my co-pending application Serial No. 257,295, filed February 20, 1939, entitled "Oscillator."

One object of my invention is to provide a member which may be used in a liquid to expeditiously precipitate entrained materials therein or to hasten the chemical combinations of the materials closely associated in the fluid, the apparatus consisting essentially of a member having considerable length in proportion to its lateral dimensions and having a cross-sectional contour other than circular, means being provided to cause the member to oscillate about its longitudinal axis or revolve through less than a complete revolution first in one angular direction and then in the opposite angular direction through less than a complete circle, these revolutions or oscillations being repeated rapidly whereby projections extending transversely of the member engage the mass in which the member is at least partially immersed, such engagement being in alternately opposite directions whereby to vibrate the mass thus causing it, in the case of concrete or the like, to become plastic and flowing or in the case of liquids causing particles entrained therein to coalesce and become rapidly precipitated out of the fluid or to cause materials intimately associated in the fluid to combine chemically more rapidly than they would otherwise combine if not subjected to such vibrations or oscillations.

Another object of my invention is to provide a member that is other than round and which is oscillated on its longitudinal axis, the member making surface with a material to impart thereto rapid vibrations due to the oscillations of the member whereby the material will become flowing and plastic under the vibrating influence of the oscillating member, thus resulting in the elimination of entrapped air and surplus water from a material such as Portland cement concrete, the member, if desired, being also arranged to strike off and smooth the surface of the mass as the oscillating member is propelled across the material.

The apparatus may also be arranged with the oscillating member elevated above the material to be treated, connected by suitable connectors to

other members in contact with the material to be treated or at least partially immersed therein whereby the latter members are given oscillations transverse to their long axes. The latter members may be either tubular for immersion in the material, or one may be in the form of a screed or strike-off member, or both may be screeds or strike-off members.

Still another object is to provide means whereby the oscillations of the member are not transmitted to a supporting means therefor, and to provide means in the form of a plurality of rotating out-of-balance weights so related to each other that reversing rotary forces, or force-couples, moving less than a complete revolution about an axis, are imparted to the oscillating member which therefore revolves about its instantaneous axis in reversing directions, each movement being less than a complete revolution, and in continuing cycles, thereby vibrating the mass with which it is in contact or in which it is at least partially embedded, in alternately opposite directions, in contrast to the orbital movement in complete circles which would be imparted to the material were the member activated by a single out-of-balance revolving weight.

A further object is to provide an apparatus for placing concrete or a like material in a slab such as a roadway by means of a container extending across the area of the slab, the forward wall of the container extending below the finished surface elevation of the slab and a vibrator being provided therefor to impart oscillations to the material in the container and to the material adjacent the lower edge of the forward wall thereof.

A further object is to provide the rearward wall of the container extending downwardly to a predetermined elevation above the finished surface of the slab, the aperture thus remaining being closed by an oscillating member having its lower surface substantially at the desired level of the finished surface of the slab and the oscillating member being effective to vibrate the material of the slab with which it is in contact and to strike off and reduce its upper surface to the desired finished level upon advancement of the apparatus across the slab.

Other objects, purposes and characteristic features of the present invention will be in part obvious from the accompanying drawings and in part pointed out as the description of the invention proceeds. In describing the invention in detail, reference will be made to the accompanying drawings, in which like reference characters

designate corresponding parts throughout the several views and in which:

Figure 29 is a vertical cross sectional view of another form of my apparatus.

Figure 30 is a vertical cross sectional view of another form of my apparatus.

On the accompanying drawings I have used the reference character OM in Figures 1—6 of the drawings to indicate an oscillating member. This member may take various forms, some of which will be specifically described by reference numerals. The form of oscillating member shown in Figures 1, 2, 4 and 5 is an elongated bar

having a shank 10 and a plurality of wings or projections 12 extending laterally from the longitudinal axis of the oscillating member OM.

The shank 10 of the oscillating member OM is adapted to be secured in a boss 19 of a casing 20 as by means of a set screw 21. The casing 20 has a cover 22 and journaled in the casing and its cover are shafts 23.

The shafts 23 are spaced from the axis AOM of the oscillating member OM preferably diametrically opposite each other. A drive shaft 24 is journaled preferably on the longitudinal axis AOM of the oscillating member OM.

Off center weights 25 are mounted on the shafts 23 and are rotated in similar angular directions about shaft 23 by gears 26 and 27. The gears 26 are mounted on the shafts 23 and are rotated by a gear 27 mounted on the drive shaft 24.

The gears 26 and 27 effect timed rotation of the shafts 23 at the same speed, while the off center weights 25 are mounted on the shafts so that they are always in opposed relation to each other. Two of these opposed positions are shown by solid and dash lines respectively.

For rotating the drive shaft 24, I provide a suitable motor 28 connected as by a large tube of rubber or the like 29 to the casing cover 22. The purpose of this type of connection is to minimize vibrations and oscillations of the casing 20 being imparted to the motor 28. For the same reason I provide a rubber sleeve 30 as an operative connection between the drive shaft 24 and the shaft 31 of the motor 28. For supporting the tool thus far described, by hand, a pair of handles 32 may be provided on the motor 28.

Practical operation of the apparatus shown in Figures 1 to 6

The oscillating member OM is inserted in the material to be vibrated and the motor 28 energized for imparting rotation through the gearing to the off center or out of balance weights 25. Obviously when the weights are in the positions shown in Figure 4, the centrifugal force generated by the left hand weight will be in the direction of the arrow *a*, which is diametrically opposite to the centrifugal force generated by the right hand weight as indicated by the arrow *b*. The forces indicated by the arrows *a* and *b* fall in the horizontal axis *c* and since I select my weights 25 so that they are of equal weight and similar shape with respect to their axes of rotation, they generate equal centrifugal forces. These forces acting in the direction of the arrows *a* and *b* will tend to rotate the oscillating member OM clockwise in Figure 4 so that the line *c*—4 intersecting the longitudinal axis AOM and the axes of the shafts 23 opens clockwise angles with reference to the line *c*.

By the time the weights 25 have rotated 90° to the solid line position shown in Figure 3, the centrifugal forces thereof, as indicated by the arrows *d* and *e*, being equal and opposite, cancel each other. Similarly, as the weights 25 rotate further to the position of Figure 5, the turning moments on the shafts 23 will be as indicated by the arrows *f* and *g*, so that line *c*—5 intersecting the longitudinal axis AOM and axes of the shafts 23 opens counterclockwise angles with relation to the line *c*, which is opposite to the turning moment of Figure 4. In other words, the tendency is to rotate the oscillating member clockwise in Figure 4 and counterclockwise in Figure 5.

Further rotation of the weights 25 to the dotted

positions of Figures 1 and 3 again causes the effectiveness of the weights 25 to cancel each other as the forces they exert would be opposite the arrows *d* and *e*. From the foregoing it is obvious that there will be a definite oscillating tendency of the oscillating member OM accomplished by out-of-balance weights without a tendency for the entire casing 20 to wobble in a circular path, as would be caused by only one out-of-balance weight mounted therein. Therefore, 10 by immersing the oscillating member OM in a mass of material to be vibrated thereby, the wings or vanes 20 thereof will impinge against the mass first in one direction and then in the opposite direction, imparting vibrations to the mass at 15 the same rate as the weights 25 revolve. It will be seen that there is no appreciable tendency to displace the longitudinal axis AOM to any outside position parallel to AOM.

The oscillating movement of the member OM 20 is prevented from being transmitted to the motor 28 and thence to the operator's hands on the handles 32 by the elastic members 29 and 30. These members absorb torsional movement of 25 the casing and of the shaft 24 and thereby prevent the transmission of reversing torques of the casing 20 and its cover 22 to the motor and vibration of the shaft 24 to the motor shaft. The collar 29 is also sufficiently elastic to permit reasonable angular deflection of the oscillating member relative to the handles 32 to secure the desired oscillating movement as illustrated in Figures 4 and 5.

With reference to the apparatus shown in Figure 1, I have found this type to be especially effective for the placement of concrete in forms where the clearance available for the insertion of a vibrator is very limited. This applies, for example, to the manufacture of concrete pipe. For such structures the forms are usually placed on a molding board with one open end up. There is usually a large amount of reenforcement between the surfaces of the forms and these surfaces are relatively close together, usually one and one-quarter to two and one-half inches apart. This restricted space combined with the presence of steel reenforcement prevents the use of the ordinary type of vibrator. Such devices have diameters too great to allow them to be inserted in the forms. In my device the oscillating member OM can be made as small in maximum lateral direction as desired and as long as necessary to reach down through the full depth of the form. As the member OM is caused to oscillate, it will act efficiently throughout its full length to the extreme depth of the form because of its strength in torsion, and any oscillating movement applied to it at any point will be carried at its full intensity throughout the length of the member. This may be contrasted to a blade or member, one end of which is given a rapid, vibrating movement laterally of its longitudinal axis. Such movement is "damped" out before the other end of the blade is reached. The blade has little beam strength, and the whipping action is killed before the other end of the blade is reached.

I have also found that when the oscillating member OM is immersed in a fluid carrying particles in suspension, the oscillations are imparted to the fluid, the particles are set into motion and presently a group of such particles will coalesce. The increased mass formed thereby will overcome the surface tension of the fluid and precipitation of the particles is thereby greatly expedited.

When the member OM is immersed in a fluid carrying a variety of materials which it is desired to be caused to enter into chemical combination, the action of the oscillator expedites the prompt intimate association of the various materials and expedites their chemical union in the same manner as the action of a catalyst.

Description of the structures shown in Figures 7 through 10

In the form of my apparatus of Figures 7 through 10 I utilize the apparatus of Figures 1 through 6 except the oscillating member OM and in Figures 7 through 10 I use reference CO to indicate the instantaneous center of oscillation of the housing 20. On one side of the housing 20 of Figures 7 and 8 I provide the lugs 31a bolted to ends of the links 32a, the other ends of which are bolted to the lugs 33 of the head 34. Projecting from the head 34 I provide the oscillating member 35 having its axis of oscillation OV approximately parallel to the shaft 24 in housing 20. The member 35 may have any shape and I show one form having the general cross section of a figure 8, the tubular parts being joined by the web 36 and having the stiffeners 37. On the housing 20 I provide the strut 39 carrying the elastic bumpers 38. On the links 32a I provide the stop lugs 40, the object being that by intermittent contact of bumpers 38 against stop lugs 40, I maintain the position of the axis OV approximately intersecting the line C—C passing through the housing 20.

Practical operation of the apparatus shown in Figures 7 through 10

The weights 25 in the housing 20, when rotated, perform in the same manner as described for Figures 1 through 6. The housing 20 will therefore oscillate around the axis CO passing through the shaft 24 and parallel therewith. These oscillations will be imparted to the head 34 through the links 32a, and motion will be induced in head 34 corresponding to the motion of housing 20.

The oscillating member 35, being attached to head 34, will receive similar oscillations, and will be subjected to torque applied in reversing cycles by the head 34. Since the oscillator 35 is torsionally rigid, such reversing cycles of torque will be equally, or approximately equally, transmitted to the free end 35a of oscillator 35. The oscillator 35 will oscillate in reversing cycles about its instantaneous axis of oscillation OV. When the oscillator 35 is at least partially immersed in a material to be vibrated, the material will be subjected to impacting oscillatory vibratory forces from the projecting edges of the oscillator 35. The form of the apparatus shown in Figures 7 through 10 is very convenient in locations where clearance for the motor 28 and housing 20 is restricted. The oscillating member 35 may of course be operated in any position, vertically, horizontally, or otherwise.

Description of the structures shown in Figures 11 through 14

In Figures 11 through 14 I show an apparatus on the order of that shown in Figures 7 through 10. The oscillating housing 20 is supported in a position with the shaft 24a (corresponding to shaft 24 of figure) disposed horizontally and carried in the supporting bearings 41 on the struts 42 which in turn through their pins 43 engage the

frame 44 of a carriage which is not otherwise shown. The shaft 24a extends through one bearing 41 and carries a sheave 45 which is driven through the belts 46 by a source of power not shown.

The downwardly extending forward links 32f and rearward links 32r from the housing 20 engage the arm 46 through their pins 47 and 48. The arm 46, corresponding to the head 34 of Figure 7 carries the parallel oscillatory members 49 and 50. The arm 46 has the instantaneous center of oscillation OV. The members 49 and 50 are usually, in operation, at least partly immersed in a material 51 to be treated. The members 49 and 50 may be of any convenient length and may be associated with any desired number of oscillating housings 20, at any desired locations. The cross sectional form of the members 49 and 50 may be of various shapes, but for this illustration I have shown an egg-shaped cross section with the small curve of the section projecting in the direction of the arrow 52 which for this illustration is also the direction of the propulsion of the members 49 and 50 through the material 51. In Figure 12, I apply the reference number 25b to the forward weight 25 of Figure 5, and the reference number 25a to the rearward weight of Figure 5, as shown in Figure 12. When the weights have rotated to their positions shown in Figure 12, the weight 25b generates the force in the direction shown at the arrow *fb*, and the weight 25a generates the force in the direction of the arrow *fa*. Force *fb* is transmitted through the forward link 32a in the direction of the arrow *fb* and moves the member 50 downward in the direction of the arrow *fbm*. Force *fa* is transmitted through the rearward link in the direction of the arrow *fa* and moves the member 49 upward in the direction of the arrow *fan*. It will be noted that the members 49 and 50 have oscillated about their instantaneous center of oscillation OV.

In Figure 13 I show the members 49 and 50 in their positions as described for Figure 12, member 49 travelling upward in the direction of arrow *fan*, and member 50 travelling downward in the direction of the arrow *fbm*. In this cycle the member 49 imparts vibrations to the material 51 in the directions of the arrows 53, while during the same cycle the member 50 imparts vibrations to the material 51 in the directions of the arrows 54. The line Y-Y passing through the axes of the members 49 and 50 slants upward as it travels from 50 to 49.

In Figure 14 I show the condition existing when the weights 25a and 25b have revolved 180° from their positions shown in Figure 12. The line Y-Y now slants downward as it passes from member 50 to member 49. The forces imparted to the material 51 during this cycle by the member 49 are in the directions of the arrows 53a, and the forces of member 50 imparted to material 51 are in the directions of the arrows 54a. It will be seen that as the members are propelled in the direction of the arrow 52, the material 51 will be subjected to two vibratory treatments, first by the member 50, and second by the member 49. The material 51 being treated will have been subjected twice to vibrations in all directions.

I may elect to use any greater number of members like 49 and 50 to subject the material 51 to a greater plurality of treatments.

I may also join the lower faces of members 49 and 50 with a diaphragm, and the member may then be conveniently used for applying vibrations to the upper surface of the material 51.

Description of the structures shown in Figures 15 through 20

In Figures 15 and 16 I show one method for supporting the members 49 and 50 of Figure 12. The shoe 55 having the lower face 56 and the vertical face 57 is arranged to travel upon the forms or fixed means 58 (which restrains that portion of the material 51 which lies below the tops 59 of the fixed means 58). Face 57 is provided with the elongated holes 60 receiving the bolts 61 which in turn engage the flange 62 on the hollow bearing 63 enclosing the elastic holder 64 engaging and carrying the shaft 65 which in turn supports the arm 46 carrying the members 49 and 50. The arm 46 is connected with oscillation or vibration producing means as shown in Figures 7 or 12. The shaft 65 engages the arm 46 at the center of oscillation OV of the members 49 and 50. Holder 64, being elastic, permits the shaft 65 to oscillate within the holder 64 without imparting any appreciable oscillation to the shoe 55. Likewise, the holder 64 will absorb any vibrations of the shaft 65 induced by shifting of the instantaneous center of oscillation OV.

The vertical face 57 of shoe 55 will restrain any material 51 the elevation of which may be above the top 59 of forms 58 and prevent the wasting of material 51 over the forms 58.

In Figures 17 and 18 I show the arm 46 provided with the stops 66, corresponding to the stops 40 of Figure 8. I also show the bumpers 67 of elastic material carried in the holder 68 which in turn is adjustably attached to face 57 of shoe 55. Bumpers 67 perform the same function as bumpers 38 of Figure 8. By lowering end 68b and elevating end 68a, the member 50 may be held in lower position than member 49, and vice versa.

In Figures 15 and 19 I show the projections 69 attached to member 49, and 70 attached to member 50. When the members 49 and 50 oscillate around the shaft 65, projections 69 and 70 will oscillate in the directions of the arrows 71 and thereby adequate vibrations will be imparted to the material 51 resting adjacent to the forms 58.

Vertical adjustment of the members 49 and 50 with relation to tops 59 of forms 58 may be accomplished in several manners. One manner may be through the vertical adjustment of the flange 62 against plate 57. Another may be through the vertical adjustment of the shoe 55 of Figure 17, where the shoe 55 through the pin 43a engages the lugs 72 adjustably mounted on the member 44a of a carriage not otherwise shown. Elevation of the shoe 55 may also be regulated by a lifting device shown here in the form of a chain or cable 73 attached at one end at 74 to face 57, the chain or cable 73 at the other end being engaged by any suitable elevating and lowering apparatus, not shown.

In addition to or in lieu of the shoes 55 to support the members 49 and 50, I may provide wheeled devices resting on the forms 58 and traveling thereover, and I may also utilize screws or hydraulic devices, or bell-cranks, to perform the operations of lifting and lowering the members 49 and 50 and determining their elevations at any particular instant.

In Figure 20 I show a diagrammatic front elevation of my apparatus as applied to the construction of roadways or slabs. The side forms 58 carry the shoes 56. The frame 75 of a carriage not otherwise shown is supplied with elevating and lowering levers 76 carrying members

77 associated with the shoes 56, and the member 78 associated with the shafts 65 of the members 49 and 50. By means of adjustments provided in members 77 and 78, the relative elevations of ends 79, 80, 81 and 82 of members 49 and 50 may be established at will, thereby providing for crowned or flat roadway surfaces, and for treating a material whose surface elevation is below the tops 59 of the forms 58.

The members 49-50 have arms 46a connected with members 20 as already explained in describing other forms.

The members 49 and 50 may be utilized for reducing the upper surface of the material 51 to any desired finished surface elevation, and for planing or screeding, or both, the material 51.

In lieu of the revolving weights of Figures 1 through 12 utilized to oscillate the housing 20 about its instantaneous center of oscillation OM, I may elect to utilize oppositely moving pistons disposed on opposite sides of the axis OM and thereby oscillate the housing 20, or I may elect to utilize any other system to accomplish the desired result in the manner shown.

In Figures 21 and 22, I show another form of my apparatus. The tubes 49 and 50 of Figure 12 have been replaced by a single surface type oscillating device, consisting of the lower flat surface 84 having the vertical pusher plate 85 with the transition curved portion 86. In the drawings I have shown the axis of oscillation OV closer to link 32f than to link 32r, and the line 32f closer to the axis C-C than is link 32r. This arrangement permits the transition portion 86 to have a less degree of amplitude than the rearward portion 87 of the plate 84. The axis OV may have any desired spaced relation with respect to links 32f and 32r.

The axis C-C may or may not be parallel to the links 32f and 32r.

In Figures 21 and 22 I show another form of the stops 40 of Figure 8. I provide the steel leaf spring 88 held by the clamp 89 of arm 46, at 88a. The end 88b of the spring 88 is held from lateral movement by the bumpers 67. Any oscillation of arm 46 about axis OV will deflect the spring 88, and the spring 88 will act as conservers of energy and assist the arm 46 in oscillating in the opposite direction on each half of the cycle of oscillation.

Description of the structures shown in Figures 23 through 30

In Figures 23 and 24 I show the oscillating housing 20 having the weights 25 actuated by a sheave 90 on shaft 24, and on the opposite side of the housing I attach a torque tube 91 extending through arms 92, 93 and 94 each of which carries the connecting rods 32f and 32r, of Figure 12. Figure 24 represents the relationship of parts at the instant the oscillating housing 20 is moving in the counter-clockwise direction so that the shafts of the weights 25 lie in the line L. The casing 20 had just previously coincided with the line R, and had rotated to the position of the line L. I have found that in certain combinations of the weight and diameter of the tube 91, and with certain combinations of the length of the tube 91, there develops, during the oscillation of the housing 20, a node in the tube 91 at the point N somewhere between the ends 91a and 91b. In other words, while the end 91b is still rotating in a clockwise direction about the tube axis OV, the housing 20 and end 91a of the tube 91 is still rotating in a counter-clockwise direction about the

axis OV. The longitudinal element NR-NRa of the tube 91 will pass through the points NR and NRA, and through the node point N. Upon reversal of the direction of rotation of the housing 20, the same element of the tube 91 will occupy the position NL-NL_a, passing through the point N. That is to say, the end 91b of the tube 91 will be half a phase behind the movement of the end 91a. The result is a node or position of no rotative or oscillatory motion of the tube 91 at the point N. This point is adjacent to the arm 93, and therefore little if any oscillatory motion will be imparted to the arm 93 and to the connecting rods 32f and 32r attached thereto.

15 In Figure 25 I show an arrangement of my apparatus which overcomes the defect indicated in Figures 23 and 24. The tube 91 attached at one end to one oscillating housing 20 extends to the point 91b at the mid-point of enveloping tube 96 and the end 91b of tube 91 is rigidly attached to the tube 96 by a diaphragm 95. Reversing rotative motion of tube 91 will be transmitted to the mid-point of tube 96 and if the tube 96 be properly proportioned as to diameter, weight and length, all of the arms 92, 93 and 94 will receive identical oscillatory motion. When convenient a construction utilizing more than one tube 91 or oscillating housings 20 may be resorted to.

20 In Figure 26 I show another arrangement of my apparatus which overcomes the defect indicated in Figures 23 and 24. In the arrangement of Figure 26 the one housing 20 shown is mounted close to the mid-point 91 of tube 98, so that reversing rotative motion of the housing 20 is so transmitted to tube 98 that all the arms 92, 93 and 94 receive identical oscillatory motion.

25 In all these arrangements it is desirable that the various members be so proportioned that their natural periods of oscillation are above the period of oscillation of the housing 20. If the period of oscillation of any principal member of the apparatus which receives oscillation is below or less than the period of oscillation imparted by the housing 20, then such member vibrates violently and may on occasion be destroyed before the frequency of operating oscillation passes through that natural period of oscillation of the member under consideration. I have found that excessive amounts of power are required to cause the frequency of oscillation to pass through the natural period of oscillation of any principal member of the apparatus, and one feature of my invention is to design the apparatus to have the natural frequency of oscillation of all principal members of the apparatus in excess of the frequency of oscillation of the working speed of the housing 20.

30 In Figure 27 I show a form of my apparatus utilizing the apparatus of Figure 26.

I provide the struts or pushers 42 like Figure 12 carrying a transverse beam 99, the strut 42 being supported by a bracket 100 and wheel 101 riding on the side forms 58. I may utilize an elevating device for the beam 99 but have not shown it in the figure in order to avoid ambiguity. I provide a hanger 102 attached to the beam 99 and supporting a rocker arm 103 by means of the pin OV. The rocker arm 103 in turn supports the strut 32f through the pin 48, and the strut 32r through the pin 47. I also provide a hanger 104 attached to hanger 105 which supports a rocker arm 108 through the pin OV and the rocker arm 108 in turn supports the strut 32f through the pin 48, and the strut 32r through the pin 47. Hanger 105 is attached to the hanger 104 by means of

bolts 106 running in slotted holes 107, whereby the elevation of the rocker arm 108 may be adjusted upwardly or downwardly for crowning the vibrator members 49 and 50. The hangers 102 and 105 through rocker arms 103 and 108 serve not only to determine the elevation of the vibrator elements 49 and 50 but also to propel said elements through or in contact with the material to be treated.

The upper ends of struts 32f and 32r are connected to arms 92, 93 and 94 by pins 31c, and thereby not only transmit the oscillations of torque tube 98 to the vibrator elements 49 and 50, but also serve to sustain the tube 98 above the beam 99. To maintain the axis of tube 98 vertically above the axis of the beam 99, I provide the vertical arms 109 attached to the beam 99 and through pins 110 engaging links 111 which in turn engage the shafts 24 and extension bars 24c of tube 98. This arrangement permits the tube 98 to vary in elevation relative to beam 99.

Through a belt 112 I drive the sheave 96 and thereby actuate the oscillator housing 20, which in turn oscillates the torque tube 98. Through the struts 32f and 32r these oscillations are transmitted to the vibrator element 50 attached to struts 32f and the vibrator element 49 attached to struts 32r.

On the beam 99 I may mount a plurality of torque tubes 98 with attached devices, and by means of the adjustable members shown may crown the various sets of vibrator elements 49 and 50 to accommodate any desired transverse curvature of the material being treated. I may also provide a plurality of beams 99 with attached devices. In lieu of the belt drive 112 shown, I may actuate the oscillator housing 20 by any other convenient means.

The vibrator elements 49 and 50 of Figure 27 may be changed to other forms of elements or combinations as hereinafter described.

In Figure 28 I show the vibrator tubes 49 and 50 with supporting struts 32f and 32r in combination with the bias attachment of Figures 21 and 22. The rocker arm 46 is provided with the bosses 88 engaging the leaf spring 88. The beam 99 is provided with the lugs 68c preventing the spring 88 from revolving about the axis OV, and thereby maintaining the elevations of elements 49 and 50 at approximate similar vertical elevation or at any deviation therefrom that may be desired.

In Figure 29 I have removed the vibrator elements 49 and 50 and have substituted screeds 113 and 114 whose vertical faces 115 are suitably attached to struts 32f and 32c and thereby maintained in vertical position. Screeds 113 and 114 may be of the general form shown in Figures 21 and 22. When the apparatus moves to the left as indicated by arrow 116 the screed 114 engages the material 51 and vibrates it in all directions as indicated by the arrows 54 and 54a. Screed 113 acts in the same manner, and the apparatus leaves the material 51 struck off to desired finished surface elevation at 117.

In Figure 30 I have removed tube 49 of Figure 28 and substituted screed 113 of Figure 29. Tube 50 engages the material 51 and vibrates it internally in all directions as shown by arrows 54 and 54a, and thereafter, the apparatus being propelled in the direction of the arrow 118, the material 51 is engaged by the screed 113 functioning the same as screed 114 of Figure 29, 75

leaving the material 51 struck off to desired surface elevation at 117.

I may also utilize a plurality of oscillating members actuated by a single actuating means, an oscillating member actuated by a plurality of actuating means, or a plurality of oscillating members actuated by a plurality of actuating means.

Having described specific embodiments of my invention, I desire it to be understood that these forms are selected to facilitate the disclosure of the invention rather than to limit the number of forms which it may assume, and it is to be understood further that various modifications, adaptations and alterations may be applied to the specific forms disclosed to meet the requirements of practice without in any manner departing from the spirit and scope of the present invention, except as set forth in the claims appended hereto.

I claim as my invention:

1. In a vibrating apparatus for material a casing, a shank having a roughened surface thereon secured at one end to the casing and having another end extending freely therefrom for immersing in the material to be vibrated, means for oscillating the shank first in one direction and then in the reverse direction about its longitudinal axis comprising two rotatable off-center weights, a shaft mounting each weight respectively on the casing adjacent and in spaced relation to said one end of the shank, said shafts being in spaced parallel relation to the axis of the shank and said off-center weights being disposed on opposite sides of their respective shafts, and power means including a drive element mounted on the casing connected to the respective shafts for rotating the shafts and weights in synchronism in the same clockwise direction whereby reversing force couples are imparted to the shank.

2. In a vibrating apparatus for material a casing, a shank having a roughened surface thereon secured at one end to the casing and having another end extending freely therefrom for immersing in the material to be vibrated, manual supporting members for supporting the apparatus in the material, means for oscillating the shank first in one direction and then in the reverse direction about its longitudinal axis comprising two rotatable off-center weights, a shaft mounting each weight respectively within the casing adjacent and in spaced relation to said one end of the shank, said shafts being in spaced parallel relation to the axis of the shank and said off-center weights being disposed on opposite sides of their respective shafts, and power means in the casing including a drive element mounted on the casing connected to the respective shafts for rotating the shafts and weights in synchronism in the same clockwise direction whereby reversing force couples are imparted to the shank.

3. In a vibrating apparatus for material a casing, a shank having a roughened surface thereon secured at one end to the casing and having another end extending freely therefrom for immersing in the material to be vibrated, manual supporting members for supporting the apparatus in the material, means for oscillating the shank first in one direction and then in the reverse direction about its longitudinal axis comprising two rotatable off-center weights, a shaft mounting each weight respectively within the casing adjacent and in spaced relation to said one end of the

shank, said shafts being in spaced parallel relation to the axis of the shank and said off-center weights being disposed on opposite sides of their respective shafts, and power means in the casing having a drive shaft in axial alignment with said shank including a drive element mounted on the casing common to both said off-center weights connected to the respective shafts for rotating the shafts and weights in synchronism in the same clockwise direction whereby reversing force couples are imparted to the shank.

4. In a vibrating apparatus for material a casing, an elongated shank having longitudinal ribs thereon detachably secured at the upper end to the casing and having the lower end extending freely therefrom for immersion in the material to be vibrated, manual supporting members for supporting the apparatus in the material, means for oscillating the shank first in one direction and then in the reverse direction about its longitudinal axis comprising two rotatable off-center weights, a shaft mounting each weight respectively within the casing above the shank, said shafts being in spaced parallel relation to the axis of the shank and said off-center weights being disposed on opposite sides of their respective shafts, and power means in the casing having a drive shaft in axial alignment with said shank in-

cluding a drive element mounted on the casing common to both said off-center weights connected to the respective shafts for rotating the shafts and weights in synchronism in the same clockwise direction whereby reversing force couples are imparted to the shank.

5. In a vibrating apparatus for material a frame adapted to be suspended adjacent the material, an elongated vibrating element having an irregular cross-sectional shape attached to the frame, having a freely extended portion within the material to be vibrated, a casing associated with the element, means for oscillating the casing and the attached vibrating element first in one direction and then in the reverse direction about its longitudinal axis comprising two rotatable off-center weights, a shaft mounting each weight respectively on the casing, said shafts being spaced in parallel relation to each other and said off-center weights being disposed on opposite sides of their respective shafts, and power means including a drive element mounted on the casing connected to the respective shafts for rotating the shafts and weights in synchronism in the same clockwise direction whereby reversing force couples are imparted to the shank.

ROBERT WILLIAM BAILY.
